No. 738,797.

PATENTED SEPT. 15, 1903.

H. HARTT.

BED MOTION FOR PRINTING PRESSES.

APPLICATION FILED APR. 28, 1902.

NO MODEL.

4 SHEETS—SHEET 1.

FIG. 1.

Detailed description: The drawing illustrates a complex mechanical assembly. At the top, a horizontal plate labeled 'P' is supported by a vertical column. A lever mechanism labeled 'K2' is attached to the column. Below this, another horizontal plate labeled 'L'' is supported by a vertical column. A lever mechanism labeled 'K1' is attached to the column. The middle section shows a horizontal plate labeled 'A'' supported by a vertical column. A lever mechanism labeled 'K3' is attached to the column. The bottom section shows a horizontal plate labeled 'E' supported by a vertical column. A lever mechanism labeled 'K4' is attached to the column. The entire assembly is mounted on a base plate labeled '5'. Various parts are labeled with letters and numbers, such as 'G1' through 'G6', 'H1' through 'H6', and 'M1' through 'M3'. A dashed circle labeled 'K5' is also present.

UNITED STATES PATENT OFFICE.

HENRY HARTT, OF CHICAGO, ILLINOIS.

BED-MOTION FOR PRINTING-PRESSES.

SPECIFICATION forming part of Letters Patent No. 738,797, dated September 15, 1903.

Application filed April 28, 1902. Serial No. 104,948. (No model.)

To all whom it may concern:

Be it known that I, HENRY HARTT, a citizen of the United States of America, and a resident of Chicago, county of Cook, and State of Illinois, have invented certain new and useful Improvements in Bed-Motions for Printing-Presses, of which the following is a specification.

My invention relates to bed-motions for printing-presses, and has for its object improvement in the reversing mechanism therefor.

My invention is illustrated in the accompanying drawings, in which—

15 Figure 1 is a partial transverse section of a printing-press, part of the mechanism being in elevation. Fig. 2 is a horizontal section of a rack-frame at its extreme position, the operating mechanism being in plan. Fig. 3 is a 20 section on line 3-3 of Fig. 2 with the rack-frame in elevation. Fig. 4 is an elevation of the reversing-crank. Fig. 5 is a section of the driving mechanism on line 5-5 of Fig. 1. Figs. 6 and 7 correspond to Figs. 1 and 4 and 25 show modified forms of construction, and Fig. 8 is a detail of the crank-pin of Figs. 6 and 7.

Supported by the press-frame A is a bed B, which runs on guides D, and over the bed B is the impression-cylinder C. Supported by 30 a bridge E and a bearing A' in the frame A is a hollow shaft F. One end of the shaft F is enlarged and provided with a chamber F⁵, which is bored out to fit the hub G⁵ of the gear G'. The enlarged portion of the shaft 35 F is provided with slots F⁶, through which pass the arms of the gears G'. Two or more of the arms of this gear are enlarged, as shown at G⁶ in Fig. 5, and are made to fit the slots F⁶. This construction permits the gear to 40 slide axially with respect to the shaft F, but holds the gear and shaft so that they rotate together.

The open end of the chamber F⁵ is closed by a plate F', which is held in position by the 45 bolts F⁴. The inner face of the plate F' is slightly counterbored to receive the slotted portion of the enlarged end of the shaft F. On the outer face of the plate F' are two lugs F², which are connected together by a cap F³. 50 The lugs F² and cap F³ might be cast in one piece solid with the plate F'; but by making the cap F³ separate it is easier to finish the

inside faces, which are lined with gibs F⁷. Inside the hollow shaft F is another shaft M, on the left-hand end of which is a crank M'. 55 The hub of this crank has a bearing in the plate F', which is bored out for this purpose. The outer end of the crank M', which carries the pin M², is finished on the sides and fits between the gibs F⁷. By this construction 60 the crank M' and pin M² are permitted to move axially with respect to the plate F', the said lugs F² and their gibs F⁷ furnishing longitudinal guides for such movement.

Power is conveyed from the pulley P 65 through a gear (not shown) to the gear L, which is secured to and drives the hollow shaft F. Secured to and turning with the gear L is a smaller gear L', which meshes with a gear K' on the shaft K. On the shaft K is 70 a cam K², which engages and moves a fork G³, which is held at a fixed axial position on the shaft M by collars G⁴. The rotation of the cam K² therefore gives the shaft M and its crank M' and pin M² a reciprocating axial 75 movement. Also on the shaft K is a cam K³, which engages a lever K⁴, which lever acts to move a collar K⁵ axially on the shaft F. The collar K⁵ is connected by bolts K⁶ to the hub G⁵ of the gear G'. 80

Secured to the bottom of the bed B is a frame H, which is provided with racks H' and H², adapted to be engaged by the gear G'. These racks are so located that they are engaged alternately by the gear G' as it is reciprocated axially by the action of the cam K³. 85

Attached to the frame H are vertical guides H³, adapted to be engaged by the pin M² on the crank M'. The cam K² is so arranged that immediately upon the gear G' arriving 90 at the end of one of the racks H' or H² the pin M² will be moved axially into the corresponding guide H³, whereupon during the succeeding half-revolution of the crank M' the bed B will be brought to a stop and have 95 its direction of motion reversed. During this stoppage and reversal of the bed the gear G' is shifted from one rack to the other by the cam K³. Immediately upon the completion of this half-revolution of the crank the 100 cam K² withdraws the pin M² from the guide H³. The bed is then free to be moved by the gear G' until the said gear comes to the other end of the racks, when the operations are re-

peated through the actions of the cams K^2 and K^3 .

It will be observed that the gear G' is not driven by a key or feather, but by the hol-

5 low shaft F through contact with the arms G^6 near the periphery. This reduces the strain at the point of driving contact on the gear, and consequently reduces the danger of loose-

10 ness in a gear that has to be shifted axially. It will also be observed that the crank M' is not rotated through the action of the shaft

M , but by means of the lugs F^2 on the disk F' .

15 As these lugs are placed opposite or near the axis of the pin M^2 and are closely adjacent to the guides H^3 , there is obtained ample strength

without making either the shaft M or the crank M' heavy. The driving of the crank-

20 pin at this place by a plate or disk carried on a large shaft avoids any danger of springing and holds the pin securely at a definite position with respect to the gear G' . This ins-

ures the proper engagement of the pin M^2 and gear G' when shifted, as previously de-

25 scribed, by the action of the cams K^2 and K^3 . It also relieves the shaft M of all strain, ex-

cept that necessary to move the crank-pin M^2 to and from engagement with the guides H^3 .

In Fig. 6 is shown a modification by which the rack-frame is divided into two parts, H

30 carrying the racks H' and H^2 , and H^4 carrying the guides H^3 . These two parts are sepa-

rated and the bridge E inserted between them. This reduces the overhang of the crank beyond the bearing of the shaft F . An-

35 other modification shown in the same figure and also in Figs. 7 and 8 is that the crank-

pin is held in a cylindrical socket in the plate F' , and the function of the crank M' is to slide the pin axially to and from engagement

40 with the guides H^3 . In this case the crank-

pin M^2 is made up of a cylinder M^5 and a roller M^4 , which are held together by an internal pin M^3 and nut M^6 . In the cylinder M^5 is a hole M^7 , which is engaged by a pin M^8 in

45 the end of the crank M' . The socket F^9 is slot-

ted at F^{10} to permit of the movement of the pin M^8 and its engagement with the crank-pin.

What I claim is—

1. In the reversing mechanism of a printing-
50 press, a crank-pin, a hollow shaft arranged to revolve said pin about the center of said shaft, and a second shaft within said hollow shaft and arranged to move said pin axially with respect thereto.

55 2. In the bed-moving mechanism of a printing-press, the combination with a reciprocating bed, a frame secured to said bed and provided with horizontal racks and vertical guides, a gear for engaging said racks, and a

crank-pin for engaging said guides, of means 60 for shifting said gear from one rack to another, and independent means for shifting said crank-pin to and from said guides.

3. An axially-movable shaft, a crank secured to said shaft and provided with a crank- 65 pin, and a second shaft consisting of a tube surrounding the first-mentioned shaft and provided with longitudinal guides adapted to engage and drive said crank at a point adjacent to said pin. 70

4. In the bed-moving mechanism of a printing-press, a frame providing upper and lower racks, vertical guides secured to said frame and located opposite the ends of the racks, a gear adapted to engage said racks, a crank- 75 pin adapted to engage said guides, a shaft arranged to drive said gear and said pin, a cam for moving said gear from one rack to the other, and a second cam for moving said pin to and from engagement with said guides. 80

5. In the bed-moving mechanism of a printing-press, the combination with a reciprocating bed, of a frame secured to said bed and provided with vertical slots serving as guides, a crank-pin adapted to fit into said guides, 85 and means for moving said crank-pin axially so as to insert it in and withdraw it from said guides.

6. The combination with the bed of a printing-press, of a frame secured to said bed and 90 provided with upper and lower racks by which the bed is driven, a rotary shaft provided with an enlarged portion at one end, a gear driven by the enlarged portion of said shaft and movable with respect thereto so as to engage 95 the upper and lower racks alternately, a plate secured to the end of the enlarged portion of said shaft and provided with a guide on its outer face, a crank-pin supported within said guide and axially movable with respect thereto, and bed-reversing guides located opposite the ends of the racks and adapted to be engaged and disengaged by the axial movement of said crank-pin. 100

7. In the bed-moving mechanism of a printing- 105 press, the combination with a reciprocating bed and vertical guides rigidly secured thereto, of a shaft, a gear and a crank-pin driven by said shaft, and means for shifting said gear and said crank-pin relatively with 110 respect to each other and axially and independently with respect to said shaft.

Signed at Chicago, Illinois, this 23d day of April, 1902.

HENRY HARTT.
